LIGHT SOCKET

Halbert W. Hoard, Fox Point, Wis.

Application July 15, 1949, Serial No. 3,931

Term of patent 14 years

(Cl. D26—1)

To all whom it may concern:

Be it known that I, Halbert W. Hoard, a citizen of the United States, residing at Fox Point, in the county of Milwaukee and State of Wisconsin, have invented a new, original, and ornamental Design for Light Socket, of which the following is a specification, reference being had to the accompanying drawing, forming part thereof.

Figure 1 is a side plan view of the light socket, showing my new design;

Figure 2 is a top plan view of the light socket shown in Figure 1;

Figure 3 is a front elevational view of the light socket shown in Figure 1;

Figure 4 is a rear elevational view of the light socket shown in Figure 1; and

Figure 5 is a bottom plan view of the light socket shown in Figure 1.

I claim:

The ornamental design for a light socket, as shown.

HALBERT W. HOARD.
